UNITED STATES PATENT OFFICE

2,384,045

DESK WITH TYPEWRITER ATTACHMENT

Maynard H. Raggio, Chicago, Ill.

Application September 21, 1942, Serial No. 459,091

10 Claims.

(Cl. 312—29)

This invention relates to a desk having a typewriter attachment, and more particularly to such desk in which the typewriter platform when the typewriter is not in use is swung downwardly to substantially a vertical position and then slid backwardly into the typewriter receiving compartment, and in which attachment the ordinary type of hinge is eliminated and substantially no metal need be used unless desired.

In the old type of typewriter desk having a swinging and sliding typewriter platform, the guideways for enabling the sliding movement of the same back into the compartment, were of such character that considerable binding and cramping between the runner and the guideways occurred, and in which desk the ordinary metal hinge was used to enable swinging of the typewriter platform from a vertical to a horizontal position. Also in such old type of desk considerable metal was used, which is now difficult to obtain.

In the present invention I have provided a structure which is capable of substantially eliminating metal, except for screws and the like, and I have eliminated the metal hinges for the typewriter platform, and at the same time have strengthened both the platform and the sliding and swinging parts, lessened the sliding friction and eliminated the binding and cramping action that would be present with the old type of hinge mounting. If metal, plastics or other suitable materials were available and desirable, the same may be used without departing from the spirit of my invention.

Among the objects of my invention are to overcome disadvantages and utilize advantage, referred to above and pointed out more in detail later herein.

A further object is to provide a novel means for mounting the typewriter platform with relation to the guideway, for enabling vertical swinging and longitudinal sliding movements, without the use of metal hinges, or parts that would produce undue friction or binding during sliding movement.

Another object is to provide means for automatically preventing looseness or vibration of the typewriter platform when in horizontal position.

A still further object is to provide a novel form and arrangement of extension bar, and connection of the same with relation to the typewriter platform and the guideway in the compartment.

Yet another object is to provide novel means for releasably locking the typewriter platform in horizontal position, and readily unlocking the same without the necessity of using the hands.

Another object is to provide a swinging door for the front of the well, which when swung to open position is provided with means for supporting the front end of the extension bar when extended.

5. A still further object is to provide anti-friction means for holding the lowered typewriter support in vertical position and assist in the easy sliding of the same, together with the typewriter, rearwardly into the compartment.

10. A further object is to provide a novel arrangement of extension bar which is both rotatable and longitudinally slid able in a guideway, and which bar has the typewriter platform fixed thereto so as to eliminate the need for metal hinges and the tendency to twist, and lessen sliding friction.

15. Other objects, advantages and capabilities inherently possessed by the invention will later more fully appear.

My invention further resides in the combination, construction and arrangement of parts illustrated in the accompanying drawings, and while I have shown therein a preferred embodiment, I wish it understood that the same is susceptible of modification and change without departing from the spirit of my invention.

20. In the drawings:

Figure 1 is a fragmentary perspective view of a corner of a desk, table or the like, having a typewriter platform and attachment embodying my invention.

25. Figure 2 is a view similar to Figure 1 but showing the typewriter platform pulled forward out of the desk and in horizontal position.

30. Figure 3 is a fragmentary front elevation of a desk or the like with the door open and showing the typewriter platform in lowered vertical position.

35. Figure 4 is a view similar to Figure 3 but showing the typewriter platform in forward and horizontal position.

40. Figure 5 is a more-or-less diagrammatic top plan view, partly in section, with the top of the desk omitted except to fragmentarily show its outline in dotted lines, and showing the typewriter platform in lowered and rearward position.

45. Figure 6 is a view similar to Figure 5, showing the typewriter platform in lowered position but pulled forward out of the compartment and just prior to raising said platform to horizontal position.

50. Figure 7 is a view similar to Figure 6 but showing the typewriter platform raised to horizontal position.

55. Figure 8 is a vertical transverse section on the

line 8-8 of Figure 7 looking in the direction of the arrows.

Figure 9 is an enlarged fragmentary vertical section on the line 9-9 of Figure 7.

Figure 10 is a further enlarged fragmentary vertical section on the line 10-10 of Figure 7.

Figure 11 is a fragmentary horizontal section on the line 11-11 of Figure 3.

Figure 12 is a view similar to Figure 11 but showing a modified form of mounting for the typewriter platform rollers.

Referring more in detail to the drawings, my invention is applied to a desk, table or the like in which a typewriter platform is to be mounted so that the platform may be housed out of sight in a typewriter compartment in the desk or the like, and when desired may be pulled forward out of the compartment and swung upwardly into horizontal position for use. The desk, as seen in Figures 1 and 2, comprises a top 1, front legs 2 and 3, one on each side of the front of the well for housing the typewriter platform 4 when the typewriter 5 is not in use, and a front swinging door 6 for closing when the typewriter platform and typewriter are pushed back into the compartment. The typewriter 5 is securely fixed to the platform 4 so that it will remain in place thereon not only when the platform is swung upwardly into horizontal position but also when it is swung downwardly into vertical position ready to be pushed rearwardly into the compartment and when in the compartment. The platform is swingably positioned at such height that when it is swung upwardly into horizontal position the typewriter will be at such height as to be convenient for use when the operator is seated facing the same at the front of the desk.

Fixed between the front leg 3 and the rear leg 1, by mortise and tenon or other suitable connecting means, is a supporting bar 8, formed of any suitable material, but preferably of plywood, and positioned just inside of the end wall 9 and at the proper height for the purposes intended. The inner vertical face of bar 8 is preferably in the same vertical plane as the inner faces of legs 3 and 7 so that, as will be later explained, the extension bar 10 (preferably of wood but not limited thereto) may be slidably moved forwardly inside of leg 3.

Firmly secured to the inner face of bar 8 by wood screws 11, or other suitable fastening means, are two elongated guide rails 12 and 13, formed preferably of wood, but might be made of other material if desired. Guide rail 12 in its lower face is formed with a groove 14 extending longitudinally throughout its length and arcuate in cross section as seen in Figures 9 and 10. A similar groove 15 is formed in the upper face of guide rail 13. As shown in Figure 8, guide rails 12 and 13 are vertically spaced apart such distance that the transversely arcuate grooves 14 and 15 receive the rounded portion 16 of the extension bar 10 with a sliding fit, but not too loose. As seen in Figures 1 to 4, 8 and 9, that portion of the extension bar 10 to which the typewriter platform 4 is secured is flattened on the two diametrically opposite sides 17 and 18, said platform being secured by screws, bolts or other suitable fastening means to the flat side 17. The bottom of the extension bar 10 at its forward end for a short distance will be round to rotatably seat in the groove of block 23. As will be understood from Figure 8, these flattened portions of extension bar 10 extend forwardly from near the middle of desk leg 3 when the typewriter platform is pulled

forwardly out of the compartment to its extreme position, except the front end of the flattened side 18 as explained above. When in this position it will be understood that the platform 4 may be swung from its lowered vertical position, upwardly to horizontal position to present the typewriter for use. This upward swinging movement is made possible by rotation of the round portion 16 of extension bar 10 in the oppositely facing arcuate grooves 14 and 15, see Figure 9. Also, as will be understood in Figure 3 when the platform 4 is swung downwardly to vertical position, the rounded sides 19 and 20 of the forward portion of the extension bar 10, between the flattened portions 17 and 18, will be at the top and bottom (the flattened faces then being in a vertical position at the two sides) and will slidably fit the arcuate grooves 14 and 15 of the guide rails 12 and 13 when the typewriter platform and its typewriter are pushed rearwardly into the compartment of the desk, and thus enable such sliding movement.

In order to tighten the extension bar with relation to the guide rails when the typewriter platform is in horizontal position, and thus automatically eliminate vibration between these parts when the typewriter is in use, the rounded rear end portion 16 of the extension bar 10 is formed on two of its diametrically opposite sides with cam shaped surfaces 21 and 22 (see Figure 10) which, when the platform is forward and raised to horizontal position and the extension bar rotated by that amount, will exert a tightening action against the arcuate faces of grooves 14 and 15. This will hold these parts tight against vibration when the platform is in horizontal position, and when the platform is swung downwardly to vertical position will loosen these parts sufficiently to enable the rearward sliding of the extension bar with relation to the guide rails when the platform and typewriter are being pushed rearwardly into the compartment.

As seen in Figures 1 and 2, there is fixed to the swinging door 6, at the front edge on the inner face in alignment with the lower face of the extension bar, a supporting block 23 formed in its upper face with an arcuate groove 24 to receive the front end of the extension bar to support the same and relieve it from bending strain or cramping that might otherwise result from the weight of the platform and its attached typewriter. The door 6 is so hinged that when it is swung to its furthermost outward position the block 23 will be in proper alignment to receive the forward end of the extension bar as will be understood in Figures 2 and 3. The groove 24 in block 23 is of sufficient depth that the rounded outer end of the flattened face 18 of the extension bar will facilitate ninety degrees rotation of the extension bar during movement of the platform from vertical to horizontal position. In other words the flattened face 18 terminates short of the forward end of the extension bar to provide a rounded portion for rotation in the groove 24.

To hold the platform releasably locked in horizontal position the desk leg 2 has formed therein at the proper height a slot 25 within which is mounted a latch 26 pivoted at 27 and normally forced outwardly to latching position by a coiled or other form of spring 28 as soon as the edge of the platform has been forced upwardly past the same. During such upward movement the latch 26 will be pushed in a clockwise direction in Figure 9, by the platform edge until released, the latch then snapping into latching position. The

latch 26 may be released to permit downward swinging of the platform, either by the operator lifting the weight of the platform edge off the latch and then pushing the latch inwardly by hand, or by pushing downwardly by the foot on the pedal 29, pivoted at 30, and on the same side of the pivot pulling downwardly on the rod 31, which at its upper end pulls downwardly on the arm 32 and rotates latch 26 on pivot 21 to unlatching position. Spring 28 elevates pedal 29 when the operator's foot is released.

Formed in leg 2 and slightly removed laterally from slot 25 is another slot 33 formed on an arc of a circle having as a center the center of rotation of the extension bar 40, and receiving a peg or pin 34 fixed in the edge of the platform and which pin fits in slot 33 with sufficient snugness to prevent vibration of the platform and yet permit this pin to move into this slot as the platform is raised, and leave the slot as the platform is lowered. A similar pin 35 is fixed in the opposite edge of the platform and functions in a similar manner in a similar slot 36 formed in leg 3. These two pins and slots holds the platform against vibration when the typewriter mounted thereon is in use.

The platform at the edge toward the rear of the desk is formed with an upstanding backrail 37 to approximately close the space between the platform and the compartment when the platform is in elevated position, as seen in Figures 2, 4 and 8.

To hold the platform substantially in a vertical position when lowered from its horizontal position, and to facilitate its more ready rearward movement in a vertical position into the compartment, I have provided rollers (of which there may be one or more as desired) which may be mounted at any suitable location, either upon the platform or upon the structure forming the side of the compartment. In Figure 12 these rollers 38 are shown as mounted upon the under side of the platform, they being rotatable on the axle, pin, stub or the like 39 of the bracket 40 fixed to the platform. Suitably secured on the inner corners of legs 3 and 1 is a track rail or bar 41 at the proper height to receive contact with the rollers and serve as a trackway therefor. Similar rollers 38 may be rotatably mounted in brackets 40 secured to the outer side wall of the compartment (or other desired part of the structure) as shown in Figures 3 and 11, if desired.

As will be understood, the desk will be provided with the usual top rail 42, the bottom rail 43 and other parts inherent to a desk of this general type. The latch 26 and pedal 29 may be of hard wood and the tension member 31 of rope, wire or the like if desired, or if metal or other material is available the same may be used to suit the wishes of the manufacturer.

Having thus disclosed my invention, I claim:

1. In a desk having a typewriter compartment, a typewriter attachment having a generally cylindrical extension bar, a typewriter platform fixed to the outside longitudinal surface of the forward end portion of the extension bar, a guide rail construction extending approximately the length of the compartment and secured along one side thereof, said guide rail construction comprising a pair of vertically spaced rails each having an arcuate groove facing the groove in the other and extending the length of the guide rail, the extension bar projecting rearwardly from the platform and being rotatable and longitudinally slidable in said grooves, the forward end portion

of the extension bar where it is fixed to the platform being flattened, the side of the platform contacting the extension bar passing closely along one lateral face of the lower rail when the platform is being pushed into or pulled out of the compartment, the generally cylindrical contour of the extension bar enabling the bar to have slight rotational movement in the grooves to prevent binding or cramping when the platform with its typewriter in lowered position is being moved into or out of the compartment.

2. In a desk having a compartment provided at its front with a hinged door having a support block formed with a curved recess, a typewriter attachment comprising a typewriter platform, a generally cylindrical extension bar fixed at its outer face to the platform which is laterally offset from the axis of rotation of the bar, the bar extending rearwardly from the platform, a pair of vertically spaced apart guide rails secured to a side of the compartment and each having a longitudinally extending groove of arcuate shape in cross section, said grooves facing each other, said bar being rotatable and longitudinally slidable in said grooves and having a curved forward end to rotatably rest in the recess of the block when the platform is pulled forwardly to its outer position to form a support when the platform is being swung upwardly to operative position.

3. A typewriter attachment adapted to be mounted in a compartment of a desk and the like, comprising a typewriter supporting platform, a generally cylindrical extension bar secured to one side portion of the platform and extending rearwardly therefrom, and a guide rail construction adapted to be secured to a side of the compartment and having vertically spaced arcuate surfaces between which the extension bar is rotatable and slidable, said extension bar having a non-circular portion to cause the bar to tighten between said arcuate surfaces when the platform is pulled forwardly and swung upwardly to operative position to prevent vibration.

4. In a desk having a compartment and legs one of which legs is formed with a slot, a typewriter attachment comprising a supporting platform swingable to raised position, a generally cylindrical extension bar secured to one side portion of the platform and extending rearwardly therefrom, and a guide rail construction secured to a side of the compartment and having vertically spaced arcuate surfaces between which the extension bar is rotatable and slidable, said platform having a projection in registry with the slot of the desk leg and extending thereinto when the platform is in raised position, said projection and slot having a slidably tight fit to hold the platform against vibration when the typewriter is in use.

5. In a desk having a compartment and legs two of which legs are positioned one on each side of the front of the compartment and each of said last mentioned two legs having a slot, a typewriter attachment comprising a typewriter supporting platform swingable to raised position, a generally cylindrical extension bar secured to one side portion of the platform and extending rearwardly therefrom, and a guide rail construction secured to a side of the compartment and having vertically spaced arcuate surfaces between which the extension bar is rotatable and slidable, a pair of projections on the platform, said projections extending in said slots respectively in said raised position of the platform, the projections being slidable in the slots as the platform

is swung to raised position, but tight enough therein to prevent vibration when the typewriter is in use.

6. In a desk having a typewriter receiving compartment and legs one of which legs at the front of the compartment is formed with a slot, a typewriter attachment comprising a typewriter holding platform, a generally cylindrical extension bar fixed to the platform and extending rearwardly therefrom, a guide rail construction secured to a side of the compartment and having a longitudinally extending and transversely curved groove in which the extension bar is rotatably and longitudinally slidably mounted, the platform being swingable to horizontal position when pulled forward out of the compartment, a latch for releasably holding the platform in horizontal position, a pin in the platform projecting into the slot with such snugness as to prevent longitudinal vibration, the upper end of the latch being cam shaped to hold the pin against the top end of the slot and prevent vertical vibration, and spring means for normally urging the latch into latching position.

7. A typewriter attachment adapted to be mounted in a compartment of a desk and the like, comprising a typewriter supporting platform, a generally cylindrical extension bar secured to the platform and extending rearwardly therefrom, and a guide rail construction adapted to be secured to a side of the compartment and having vertically spaced arcuate surfaces between which the extension bar is rotatably and longitudinally slidably mounted, the adjacent face of the platform being secured to the outer face of the extension bar to be laterally offset from the center of rotation thereof, the extension bar being rotatable with relation to said arcuate surfaces at all positions of its longitudinal sliding movement.

8. In a desk having a compartment, a typewriter attachment comprising a typewriter supporting platform, a generally cylindrical extension bar having one of its outer faces secured to one side portion of the platform so that the platform adjacent face is laterally offset from the axis of rotation of the extension bar, the extension bar extending rearwardly from the platform, a guide rail construction secured to a side

of the compartment and having vertically spaced arcuate surfaces facing each other and between which surfaces the extension bar is rotatably and longitudinally slidably mounted, the spaced arcuate surfaces extending the greater part of the width of the desk, and means for holding the platform in elevated operative position when the platform is pulled forwardly and swung upwardly.

9. In a desk formed with a compartment construction having side walls and a rear end wall, a typewriter attachment comprising a pair of vertically spaced apart guide rails fixed to said compartment construction adjacent one of said side walls and extending approximately the width of a side wall, the upper edge of the lower guide rail and the lower edge of the upper guide rail each having a longitudinally extending and transversely formed arcuate groove, a typewriter platform, a generally cylindrical extension bar fixed at one of its forward outer faces to said platform so that the platform is laterally offset from the axis of rotation of the extension bar, the extension bar extending rearwardly from one side of the platform, said extension bar being rotatable between said upper and lower guide rails at all positions of its longitudinal sliding movement to enable the typewriter platform to be moved forwardly from a lowered position within the cabinet to an outer position and then swung upwardly to a position for use and may be lowered and moved rearwardly into the cabinet.

10. A typewriter attachment adapted to be mounted in a compartment of a desk and the like, comprising a typewriter platform, a guide rail construction adapted to be secured to a side of the compartment and having a pair of vertically spaced longitudinally extending and transversely curved grooved members, a generally cylindrical extension bar fixed to said platform and being slidable between said grooved members and rotatable therebetween when the platform is pulled out of the well to enable it to be swung upwardly into horizontal position, and a cam surface on said extension bar to grip the grooved members to prevent vibration when the platform is in horizontal position.

MAYNARD H. RAGGIO.
